UNITED STATES PATENT OFFICE

LAWRIE L. WITTER, OF BOSTON, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed November 14, 1930. Serial No. 495,701.

This invention relates to safety razors, and more particularly to a razor so constructed that it may be quickly adjusted from shaving position to rinsing position, and vice versa.

5 While my invention is not limited to any of the various known types of safety razors, it is particularly applicable to and is herein illustrated in connection with the new Gillette safety razor. Among other improvements featured in this razor is a rust-proof blade which needs only to be rinsed after shaving, thus eliminating the blade removing and drying operations heretofore necessary. When this razor is to be rinsed, the 10 parts are released from their shaving position sufficiently to permit the flexed blade to return to its normal plane contour and to thereby become spaced from the guard. The blade may be rinsed while it is thus loosely held between the cap and guard or, if desired, the rinsing operation may be facilitated by turning the guard to a position transversely of the blade and cap. Heretofore it has been necessary for the user to guess when 15 the handle has been released sufficiently to perform this rinsing operation and very often the releasing is carried so far as to permit the several parts of the razor to become entirely disassembled and fall to the floor. One of the 20 objects of my invention is to provide a simple stop construction for definitely limiting this releasing operation to the proper blade rinsing position, such construction permitting the operator to quickly rinse the razor and blade 25 without fear of disassembling the parts.

The Gillette type razor comprises a cap and a guard adapted to hold a blade therebetween and a handle for threadedly engaging a stud on the cap to clamp the blade in shaving position between the cap and guard. When the handle is unscrewed, it backs away from the guard along this stud and, in accordance with 30 my invention, I provide cooperating stop means on the handle and stud for limiting this movement to the position required for rinsing the blade. The construction comprising my invention is also such that in this position of the parts the stud and cap are firmly supported by the handle and, furthermore, permits a complete separation of the parts when

it is desired to remove or change the blade. The provision of an improved safety razor embodying these novel features comprises a further object of my invention.

In the accompanying drawing I have illustrated certain specific embodiments of my invention but it will be understood that the invention can be otherwise embodied and that the drawing is not to be construed as defining or limiting the scope of the invention, the 55 claims appended hereto being relied upon for that purpose.

Referring to the figures of the drawing, Fig. 1 is a fragmentary perspective view of a razor embodying my invention;

Fig. 2 is an elevation thereof, partly in section, showing the razor clamped for shaving;

Fig. 3 is a view like Fig. 2 but showing the 60 razor released for rinsing;

Fig. 4 is a sectional view taken on line 4-4 of Fig. 3;

Fig. 5 is a view like Fig. 2 but showing a modified construction;

Fig. 6 shows the razor of Fig. 5 released 70 for rinsing and the guard turned to a relatively transverse position; and

Fig. 7 shows a further modification.

The form of my invention shown in Figs. 1 to 4 of the drawing will be first described. 75 This razor comprises a cap 10, a guard 12, a blade 14 between the cap and guard, and a handle 16. The cap and guard are relatively located by means of a centrally disposed rib 18 on the inner face of the cap cooperating with and extending into a groove 20 in the guard. The blade is located by means of a centrally disposed slot which fits over this rib. Also projecting from the inner face of the cap is a stud 22 provided with a thread 24 80 engaged by the threaded end of the handle. In Fig. 2 the handle is illustrated as fully tightened onto the thread 24 and the razor is thereby clamped into shaving position. It will be noted that the blade is normally plane, as shown in Fig. 3, but is flexed to a transversely curved position when clamped in 85 shaving position between the cap and guard. When it is desired to thoroughly rinse the razor following the completion of a shave and

before laying the razor away, the handle is unscrewed to a position permitting the blade to return to its plane shape and to be held loosely between the cap and guard. One of the novel features of my invention resides in the means now to be described for limiting the unscrewing of the handle to this rinsing position.

The stud 22 has a plane cylindrical portion 10 extending into and fitting the bore 26 in the handle. This plane portion of the stud is annularly grooved at 28 to provide an annular shoulder 30 and a resilient detent or latch 32 mounted on the handle has an inwardly 15 extending end adapted to engage within this groove when the handle reaches the proper rinsing position. This position is illustrated in Fig. 3, wherein the detent is engaged within the groove and against the shoulder 30. The detent 32 is shown as constructed of 20 spring metal and has a longitudinally-disposed shank by which it may be secured to the handle, an intermediate loop or raised portion 34, and an inturned end shaped to engage the stud 22 of the cap. The stud portions at 25 both sides of the groove 28 are cylindrical and closely fit the walls of the bore 26 whereby the stud and cap are firmly supported.

The operation of this form of the invention 30 is believed to be quite obvious. To bring the clamped razor of Fig. 2 to the rinsing position, the operator merely unscrews the handle, retracting the same until the resilient 35 detent 32 drops into the groove 28, at which time the thread engagement at 24 is released and the blade is returned to its plane and free position. The blade may be rinsed with the parts in the position shown in Fig. 3 or any 40 of the parts 10, 12 and 14 may be rotated to any desired position on the handle. When the parts are to be returned to the shaving 45 position, the operator need only press the handle toward the guard, whereupon the detent will yield outwardly and ride up the inclined portion of the stud and permit the threads to re-engage. When it is desired to 50 disassemble the parts for removing or replacing the blade, an instrument may be inserted beneath the raised portion 34 of the 55 detent and lift the detent from the groove and thus permit the stud 22 to be withdrawn. The inner end 36 of the stud is also preferably beveled or rounded to automatically force the detent outwardly when reassembling the parts.

While in the form of the invention shown 60 in Figs. 2 and 3 the thread engagement between the handle and cap stud is entirely released when the parts are in the rinsing position, it may be quite desirable to maintain this thread engagement. Such a modification, which is shown in Figs. 4 and 5, will now be described. This razor comprises a cap 40, a guard 42, a blade 14 between the 65 cap and guard, and a handle 44. The blade

14 is the same as above described and is located in like manner. A stud 46 projects from the inner face of the cap and is engaged within a cylindrical bore 48 in the handle. The outer end of the bore is in threaded engagement with a thread 50 on the stud and, as shown in Fig. 5, the handle is fully tightened onto this thread and the razor is thereby clamped into shaving position. Releasing the parts to the rinsing position is performed by unscrewing the handle in the same manner as above described.

An intermediate portion of the stud 46 is reduced in diameter to provide a shoulder 52 and a reduced cylindrical stem portion 54 between the shoulder and thread. A resilient 70 detent 56 on the handle has an inwardly extending end engaging the portion 54 and when the handle is unscrewed this end engages the shoulder 52 when the parts have become separated to the proper rinsing position. By referring to Fig. 6 it will be noted that the thread engagement at 50 is maintained and when the guard has been swung to the transverse position shown, the handle may be tightened thereagainst. In such position the blade rests on the cap rib 58 and the end portions of the blade are freely exposed 75 for rinsing. It should also be noted that in this position the parts are all held securely together. The guard is held firmly against the cap rib, the blade being loosely supported on the rib. The stud 46 is supported at two 80 widely spaced positions along the bore 48, namely on the thread 50 and by engagement of the top portion of the shoulder 52 with the wall of the bore. When returning the parts to shaving position, it is only necessary to slightly release the handle, swing the guard to shaving position, and then tighten the 85 handle to the position of Fig. 5.

The shoulder 52 has been shown as beveled whereby in disassembling the razor it is only necessary to force the handle outwardly with sufficient effort to raise the detent over this shoulder. It will be understood, however, that either shoulder 52 or 30 may be straight or beveled, as may be desired. The outer end 90 60 of the stud 46 may also be rounded or beveled, whereby to release the detent 56 when reassembling the parts.

Other and various modifications may be resorted to in constructing my invention. For example, the detent, instead of being resilient, may be a removable element, as in Fig. 7. In this construction the cap stud 70 is reduced in diameter at 72 and a screw 74 threaded into the handle has its inner end engaged within this reduced portion in a manner to cooperate 100 with the shoulder 76. The screw may be removed when it is desired to withdraw the stud. This construction is otherwise like that of Figs. 5 and 6 except that the shoulder 76 is straight like the shoulder 30. When the handle 78 is unscrewed, the detent 74 engages 105 110 115 120 125 130

against the shoulder 76 before the thread engagement with the stud 70 is broken, the handle thereby being positively locked to the cap when the parts have reached a releasing position sufficient for rinsing. It may, furthermore, be pointed out that if in unscrewing the handle the razor is held by grasping the guard, the handle will automatically turn the cap and blade to the transverse position 10 shown in Fig. 6 when the handle reaches its locked position.

Having thus described my invention, what I claim as new and desire to secure by Letters Patent is:

- 15 1. A safety razor comprising a cap having a single screw thread formed integrally thereon, a guard, a threaded stem cooperating with the cap screw thread and operative thereby to clamp the cap and guard together with 20 a blade therebetween, inter-engaging means on the cap and guard for preventing their relative rotation about the stem axis when in blade clamping position, and stop means for limiting the separating movement of the cap 25 and stem in a direction axially of the stem to a position wherein the cap and guard may be given a relative rotation about the stem axis while retaining the blade therebetween and adjacent to the clamping faces thereof.
- 30 2. A safety razor comprising a cap having a screw threaded stem extending rigidly outward from one face thereof, a guard having a cooperating face and a hole for receiving said stem, a handle so threadedly engaging the stem that the tightening thereof forces said faces into gripping engagement with a blade held therebetween, and cooperating stop means on the handle and stem for limiting the separation of the cap and 35 stem axially of the stem to a position wherein the gripping action on the blade is released but the said threaded engagement maintained, the cap and guard 40 being relatively rotatable about the stem axis in said released position.
- 45 3. A safety razor comprising a cap having a screw threaded stem extending rigidly outward from one face thereof, a guard having a cooperating face and a hole for receiving said stem, said faces being curved for flexing a normally plane blade to 50 cavo-convex shape therebetween, a threaded handle for engaging the stem and clamping the parts in said blade flexing position, and transversely extending means within the handle cooperating with a shoulder on the 55 stem for limiting the separation of the cap and guard axially of the stem to a position wherein the blade is released and an axis supplied for relative rotation of cap and guard.
- 60 4. A safety razor comprising a cap having a screw threaded stem extending rigidly outward from one face thereof, a guard having a cooperating face and a hole for receiving said stem, a threaded handle for engaging the stem and clamping the cap and 65 guard together with a blade gripped between 70 said faces, and a movable detent extending inwardly of the handle and cooperating with a shoulder on and extending about the stem for limiting the separation of the cap and guard to a position wherein the gripping 75 action on the blade is released, the thread on the stem being between the shoulder and cap.
- 80 5. A safety razor comprising a cap having a screw threaded stem extending outwardly from one face thereof, a guard having a cooperating face and a hole for receiving said stem, a handle so threadedly engaging the stem that upon tightening of the handle its end engages the guard and forces 85 said faces into gripping engagement with a blade held therebetween, and cooperating stop means including a movable detent on the handle and an annular shoulder on the stem for limiting the separation of the cap and guard to a position wherein the gripping action on the blade is released.
- 90 6. A safety razor comprising a cap having a screw threaded stem extending rigidly outward from one face thereof, a guard having a cooperating face and a hole for receiving said stem, a handle so threadedly engaging the stem that the tightening thereof forces said faces into gripping engagement with a blade held therebetween, and cooperating stop means on the handle and stem for limiting the separation of the cap and guard 95 to a position wherein the gripping action on the blade is released but the said threaded engagement maintained, the cap and guard 100 being relatively rotatable about the stem axis in said released position.
- 105 7. A safety razor comprising a cap having a screw threaded stem extending outwardly from one face thereof, a guard having a cooperating face and a hole for receiving said stem, a threaded handle for engaging the stem and clamping the cap and guard together with a blade gripped between 110 said faces, cooperating stop means on the handle and stem and including a shoulder on the stem for limiting the separation of the cap and guard to a position wherein the gripping action on the blade is released, and 115 cooperating surfaces on the handle and stem at both sides of said shoulder for supporting the stem and handle in axial alignment in said released position, the cap and guard being relatively rotatable about the stem axis in said released position.
- 120 8. A safety razor comprising a cap having a screw threaded stem extending outwardly from one face thereof, a guard having a cooperating face and a hole for receiving said stem, a threaded handle for engaging the stem and clamping the cap and guard together with a blade gripped between said faces, cooperating stop means on the handle and stem and including a shoulder on the 125 stem for limiting the separation of the cap 130

and guard to a position wherein the gripping action on the blade is released, and cooperating cylindrical surfaces on the handle and stem for rotatably supporting the stem in axial alignment in the handle in said released position, the cap and guard being relatively rotatable about the stem axis in said released position.

9. A safety razor comprising a cap having a screw threaded stem extending outwardly from one face thereof, a guard having a cooperating face and a hole for receiving said stem, a threaded handle for engaging the stem and clamping the cap and guard together with a blade gripped between said faces, cooperating stop means on the handle and stem and including a shoulder on the stem for limiting the separation of the cap and guard to a position wherein the said threaded engagement and the gripping action on the blade are released, and cooperating annular surfaces on the handle and stem at both sides of said shoulder for supporting the stem and handle in axial alignment in said released position, the cap and guard being relatively rotatable about the stem axis in said released position.

10. A safety razor comprising a cap having a screw threaded stem extending outwardly from one face thereof, a guard having a cooperating face and a hole for receiving said stem, a threaded handle for engaging the stem and clamping the cap and guard together with a blade gripped between said faces, and a detent extending inwardly of the handle and cooperating with a shoulder on and extending about the stem for limiting the separation of the cap and guard to a position wherein the gripping action on the blade is released, said detent being releasable to a position permitting the separation of the cap and guard to blade removing position.

11. A safety razor comprising a cap having a stem extending outwardly from one face thereof, a portion of the stem adjacent to the cap being threaded and a more remote portion thereof having an annular groove therein, a guard having a cooperating face and a hole for receiving said stem, a threaded handle for engaging the stem and clamping the cap and guard together with a blade gripped between said faces, and a resilient detent secured to the handle and engaging the stem, engagement of the detent within said groove when the handle is unscrewed being adapted to limit the separation of the cap and guard to a position wherein the gripping action on the blade is released.

12. A safety razor comprising a cap having a stem extending outwardly from one face thereof, a portion of the stem adjacent to the cap being threaded and an intermediate portion thereof between the thread and

the end of the stem being reduced in diameter to provide an annular shoulder near the end of the stem and a portion of reduced diameter between the shoulder and thread, a guard having a cooperating face and a hole for receiving said stem, a threaded handle for engaging the stem and clamping the cap and guard together with a blade gripped between said faces, and a movable detent extending into the said reduced stem portion, engagement of the detent with said shoulder when the handle is unscrewed being adapted to limit the separation of the cap and guard to a position wherein the gripping action on the blade is released.

13. A safety razor comprising a cap having a screw threaded stem extending rigidly outward from one face thereof, a guard having a cooperating face and a hole for receiving said stem, a threaded handle for engaging the stem and clamping the cap and guard together with a blade therebetween, and means including transversely extending means within the handle cooperating with a shoulder on the stem for limiting the separation of the cap and guard to a position wherein they may be given a relative rotation about the stem axis while retaining the blade therebetween and for causing the rotation of the handle to automatically rotate the cap relative to the guard without further substantial separation thereof when these parts have reached such position.

14. A safety razor comprising a cap member, a cooperating guard member, a handle so cooperating with said members that rotation thereof in one direction is adapted to clamp the members together with a blade therebetween and rotation in the opposite direction is adapted to release the clamping action, and means for locking the handle and one of the members together and against movement in either direction when the handle has been released to a predetermined position, said means being releasable to permit separation of said members.

15. A safety razor comprising a cap, a cooperating guard, a handle threadedly connected to the cap and adapted to clamp the cap and guard together with a blade therebetween, and means for locking positively the handle and cap against relative movement in either direction when the handle has been released to a predetermined position, said means being releasable to permit separation of said members.

16. A safety razor comprising a cap having a screw threaded stem member extending outwardly from one face thereof, a guard having a cooperating face and a hole for receiving said stem, a threaded handle member for engaging the stem and clamping the cap and guard together with a blade gripped between said faces, and a transversely extending movable detent on one of said members

cooperating with a substantially annular shoulder on the other member for limiting the separation of the cap and guard to a position wherein the gripping action on the blade 5 is released.

17. A safety razor comprising a cap having a threaded portion thereon, a guard, the cap and guard having cooperating curved faces for flexing a normally plane blade between them, a threaded handle engaging the cap and operative thereby to clamp the parts in blade-flexing position, and stop mechanism in addition to said threaded connection for limiting separating movement of the cap and guard to a position in which the opposed faces thereof clear the blade in its normal plane condition, said mechanism supplying an axis upon which the cap may be turned crosswise with respect to the guard.

18. A safety razor comprising a cap having a threaded portion thereon, a guard, the cap and guard having cooperating curved faces for flexing a normally plane blade between them and having a pivotal connection about which they may be relatively revolved into cross-wise relation, a threaded handle member engaging the cap thread and operative thereby to clamp the parts in blade-flexing position, and stop mechanism for limiting the separating movement of the cap and guard, when the threaded connection is released, to such an extent that the blade is returned to its normal flat shape, said mechanism being releasable to free the cap and guard for further separating movement.

19. A safety razor comprising a cap having a threaded stem with a circumferential groove therein, a guard having a hole to receive said stem, and a threaded handle member 70 cooperating with said stem and having a spring detent arranged to snap into said groove when the handle member has been unscrewed to a predetermined position.

20. A safety razor comprising a cap having a screw-threaded stem extending from a curved, blade-engaging face, a guard having a co-operating face apertured to receive said stem, a handle constructed and arranged to be threaded upon the stem to force the faces of the cap and guard into flexing engagement 80 with an interposed blade, and co-operating stop means on the handle and stem in addition to the threads thereof for limiting the separation of the cap and guard to a position in which the blade may reassume its flat condition, while maintaining the stem in position to serve as an axis for relative rotation of cap and guard.

21. A safety razor comprising a cap having a projecting stem threaded at its inner end 90 and provided with an annular groove near its outer end, a guard apertured to receive said stem, and a handle having a co-operating thread at its end for engaging the thread of the stem and a spring detent for engaging 95 the groove of the stem when the handle is unscrewed from the stem.
